UNITED STATES PATENT OFFICE.

DESIRE DACKMINE AND HECTOR MONIER, OF LEWISTON, MAINE.

THREAD CUTTER AND STOP MOTION FOR WEFT-REPLENISHING LOOMS.

Application filed January 30, 1926. Serial No. 84,880.

This invention appertains to improvements in weft thread cutters and stop motions for weft replenishing looms, being adapted for either colored threads or yarns, or for weft threads of a single color, the weft replenishing mechanism being partly shown in patents numbered 1,366,949; 1,150,477 and 1,517,513. The thread cutter and stop motion made in accord with our invention is readily applicable to the Crompton & Knowles weft replenishing looms.

In the accompanying drawings,—

Figure 1 is a plan view;

Figure 2 is a side elevation;

Figure 3 is a partial top view;

Figure 4 is a detail view;

Figure 5 is an end elevation;

Figures 6 and 7 are detail views; and

Figure 8 is a plan view of a modification.

In reference to the drawings, BB refers to the breast beam; L the lay; SB the shuttle box; S the shuttle; b the bobbin or quill; MS the magazine support; SM the stop motion and FF the filling fork, all of which are of well known construction.

Our invention relates to a filling or weft threading mechanism which is constructed to provide an automatic stop motion, the filling thread being cut when the bobbin is substantially exhausted, means being provided to hold the filling or weft thread which extends from the cutter to the selvage of the woven fabric; means being also provided to prevent the stopping of the loom when the filling fork is moved into an inoperative position; likewise to provide a protecting device for preventing a smash-up caused by an improperly working shuttle.

Generally speaking, the object of the invention is twofold: first, to provide thread cutting mechanism of simple construction for use on weft replenishing looms which is connected with the transfer mechanism of the magazine; and secondly, to provide a mechanism of simple construction combined with and a part of the thread cutting device which is provided with a stop motion which protects the mechanical parts of the cutting device from breakage and also prevents a smash-up and injury to the loom or shuttle, due to improper placing thereof.

The cutter stand 10 is provided with slots, through which pass bolts which may also be used for connecting the magazine stand to the breast beam. This stand 10 has formed integral therewith a frame with

apertures through the ends thereof for the passage of a shaft 12 which connects the frame 11 to a frame or box 13 having projecting end portions on one side and intermediate projecting portions 14 and 15 on the opposite side. The shaft 12 is in alignment with a rocker, one end of which engages with a stop lever 16. The frame 13 carries a bar 17 and has through its laterally projecting portions a rectangular opening and a circular opening for the tubular portion 18 of the bar 17. The frame 13 is also provided with an aperture for a rod 19 which is connected with an oscillatory blade 20 or cutter 20. The shafts 12 and 18 pass through springs, as shown. The bar 17 is provided on its under side with a notch 21 and the frame 13 has maintained in oscillatory engagement therewith a latch 22, said latch having tension exerted thereon by a spring 23 which may be attached to the breast beam. Said latch is also connected by means of a rod 24 with a rocker shaft or other moving part of the weft carrier magazine so that the cutter will be actuated at the proper time.

Referring to the bar 17, it will be noted that it has a depending portion 25 located intermediately or between the notch with which the latch engages and its end and that one side of the forward end portion of the bar is cut away to provide a mouth 26. The reduced portion of the bar 17 carries plates 27 and 28, one of the plates being slightly convex to provide additional pressure against the cutter 20. The cutter has a beveled edge adapted to engage with the plate 27 and a stem operating within a recess is pivotally attached to rod 19 and to the forward portion of the side of the bar 17 which carries the plates 27 and 28. The rod 19 is encircled by a spring and beyond the projecting portion of the frame 13 carries an adjustable stop 29.

When in operation, the filling detector mechanism indicates for a change of filling, and then actuates the latch rod 24 which is pulled upward from its normal position in the notch 21 and allows the bar 17 carrying the cutting mechanism, by reason of its spring, to be projected towards the lay, the cutting portion of the blade 20 then being moved beyond the mouth 26 by the stop collar 29 on rod 19 which abuts against one member of the frame 13 and operates to move the blade of the cutting device, the

filling thread being severed by the blade 20 operating between the plates 27 and 28 and holding the end of the thread which extends from the selvage.

- 5 The blade of the cutter 20 and the plate 28 conjointly provide a cutting or severing edge, and the plate 27 and the edge of the cutter being slightly out of contact, or by having a rounded or non-cutting edge, 10 merely clamps the portion of the thread beyond where it is cut to hold the end which extends from the selvage.

As the lay continues its forward movement, it comes in contact with the rigid depending portion 25 and moves the same back to inoperative position where the latch will be caught in the recess or detent, thus holding back the cutting device until the next operation. The spring attached to the pawl 20 acts to bring back the pawl in position on each operation of the shaft moving forward or backward when the pawl is released. The bar 17 returns to inoperative position as soon as the adjusting collar 29 leaves the end of the frame, the spring on the rod 19 forces the cutter blade 20 to lowered position between the plates 27 and 28, and releases the weft thread which extends from the selvage of the woven fabric adjacent to the temple cutter (not shown).

Whenever the shuttle works improperly, as, for instance, when it fails to enter far enough in the shuttle box of the loom, the end of the shuttle will strike against the end of the mouth on the bar 17 and the contact will push back the bar 17, which will cause the frame 13 to slide on the shaft 12 until it rests against its end, while the rear end of the shaft will be moved rearwardly and come in contact with the arm of the stop motion to bring the loom to a stop. The entire device is brought to an inoperative position, by means of the expansion spring which encircles the shaft 12, such spring having been contracted by pressure exerted against the member 25 of the bar 17 and when brought to an inoperative position, the pawl will catch in the notch to retain the bar 17 in such position.

It will be understood from the foregoing description that the device provides for holding the filling thread which extends from the selvage of the fabric and also for cutting the thread from the substantially exhausted shuttle, and that the movement of the lay ordinarily moves the bar to sever the threads and hold the bar carrying the cutter in an inoperative position, and in case of the movement of the cutter by contact with the wrongly positioned shuttle, the conical metal guarded end of the shuttle will enter between the jaws and force the frame rearward to actuate the stop motion.

The modification shown in the drawings, 65 Fig. 8, illustrates a change in construction

which is adapted for use with what may be termed small looms having a modified construction of shuttle boxes and stop motions and with this in view, the cutter bar has one end offset and the depending portion 25 70 which is integral with a bar depends from a point where the bar is bent laterally. With this construction, the rod 19 is bent and encircled by a spring.

We claim:

1. The combination in a thread cutter and holder for weft replenishing looms, of a movable carrier frame for a cutter bar, a cutter bar maintained in reciprocal engagement with the frame, a spring which engages the cutter bar and the frame, a thread cutter pivoted on the cutter bar, a rod which engages with the cutter, a spring and a stop on the rod for engagement with the movable carrier frame, a latch pivoted on the movable carrier frame for engagement with the cutter bar, and means for releasing the latch operatively connected with the weft replenishing mechanism of the loom.

2. In a device of the character set forth, 90 a movable supporting frame, a cutter bar maintained in slidable engagement with said supporting frame, a latch engaging the frame and the cutter bar to hold the cutter bar retracted, a depending portion on the cutter bar which is positioned to be engaged by the lay of the loom to move the cutter bar into latch engaging position, said cutter bar also being adapted to be engaged by a misplaced shuttle and when so engaged to 100 be positioned to actuate a stop motion of the loom.

3. In a device of the character described for use to provide weft holding and cutting mechanism for looms having a stop motion, 105 a stationary frame attached to a magazine stand of a weft replenishing loom, a movable frame having slidable bars associated therewith, weft thread cutting and holding mechanism carried by one of the bars, said bars occupying a position where they may be moved into normal automatic operating position by the lay of the loom and beyond the normal operating position by the lay 110 with an interposed shuttle to actuate the stop motion of the loom.

4. A combined filling or weft thread cutting mechanism for automatic weft replenishing looms and the stop motion thereof, comprising in combination a fixed supporting frame, a movable frame, a slidable bar connecting the movable frame with the fixed frame, a spring on the connecting bar, a spring actuated cutter bar associated with the movable frame, a weft thread cutter and holder, means for moving the cutter in position to hold and cut the weft thread, a rod attached to the cutter, and a spring which encircles the rod and moves the same in one direction.

5. A weft cutting mechanism for weft replenishing looms comprising in combination a movable supporting frame, a cutter bar, a weft cutter pivoted to the cutter bar, a rod 5 associated with a frame and with the cutter bar, a spring on the rod for holding the same in position which will move its weft cutter to a position with its spring under compression, a latch for holding the cutter bar against 10 movement, and a connection between the latch and the weft replenishing mechanism of the loom for releasing the latch to effect spring actuation of the cutter bar, an oscillation of the weft cutter, and a severance of 15 the weft thread from a substantially exhausted bobbin carried by a shuttle.
6. In a thread cutter for weft replenishing looms, a cutter bar supporting frame comprising a fixed section and a slidable section, a reciprocatory cutter bar carried by the slidable section, a spring on the cutter bar, a latch for holding the cutter bar against action by the spring thereon, means for releasing the latch connected with a movable 20 part of the weft replenishing mechanism of the loom, a cutter pivoted to the cutter bar, and means attached to the cutter for engagement with the slidable section of the cutter bar supporting frame to actuate a thread 25 cutter associated with the cutter bar, said thread cutter operating to effect a severance of the weft thread and to hold one end of the severed thread.
7. In a combined weft thread clamp and 30 cutter for weft replenishing looms and the stop motion thereof, the combination of a cutter bar, a frame for holding the cutter bar in inoperative and operative position, a latch connected with weft replenishing mechanism of a loom, said latch being adapted 35 to hold the cutter bar and its cutter in position to engage with a weft thread of a partially exhausted bobbin, oscillating means connected with the cutter bar to sever and to 40 hold one end of the severed weft thread, and means on the cutter bar for engagement with a misplaced shuttle to move said cutter bar to a position to operate a stop motion of the 45 loom.
8. In combination with weft cutting mechanism for replenishing looms, of a fixed support and a support maintained for movement at right angles to the length of the lay of a loom, said support being in slidable engagement with the fixed support, a spring actuated cutter bar carried by the movable support, a latch associated with the movable support for engagement and retention of the cutter bar, a connection between the latch and the replenishing mechanism of a loom 50 to effect automatic release of the latch, an oscillatory cutting blade attached to the cutter bar, means attached to the cutter blade for actuating the same to weft thread holding position, and means for actuating the cutter blade to sever the weft thread when the cutter bar is released, said releasing mechanism being actuated when the shuttle of the loom contains a substantially depleted bobbin, and a projection on the cutter bar 55 for engagement with the lay of the loom for moving said cutter bar to position where the latch will hold the cutter bar in position for the next operation.
9. The combination in a weft replenishing loom having a stop motion and a shipper bar, of a frame maintained by the breast beam of the loom, a reciprocatory bar associated with said frame, a reciprocatory frame carried by the bar, a spring operating 60 in conjunction with the latter frame for projecting the bar, a latch carried by the movable frame, means for connecting the latch with a movable part of the shuttle magazine of the loom, said latch serving to hold the 65 bar in normal position, the bar being provided on its under side with stepped depending portions so positioned relative to the shuttle box and lay of the loom that the lay will engage with one of the depending portions of the bar to effect normal movement of the bar and the higher step on the bar, and a misplaced shuttle serving to effect 70 movement of the bar to release for effective operation the stop motion of the loom.
